UNITED STATES PATENT OFFICE.

FRANK M. CHAPMAN, OF FORT EDWARD, NEW YORK, ASSIGNOR OF ONE-
THIRD TO WILLIAM J. GALLAGHER, OF SANDYHILL, NEW YORK.

PULP-SCREEN.

No. 806,640.

Specification of Letters Patent.

Patented Dec. 5, 1905.

Application filed December 31, 1904. Serial No. 239,194.

To all whom it may concern:

Be it known that I, FRANK M. CHAPMAN, a citizen of the United States, residing at Fort Edward, in the county of Washington and State of New York, have invented certain new and useful Improvements in Pulp-Screens; and I do hereby declare the following to be a full, clear, and exact description of the invention, such as will enable others skilled in the art to which it appertains to make and use the same.

My invention relates to improvements in pulp-screens.

It has for its object to provide a machine of this nature which will be capable of a larger output of a better grade than those now commonly in use.

The invention consists in providing the screen with a longitudinally-arranged flexible diaphragm adapted to be oscillated or actuated back and forth and up and down as the screen is revolved.

The invention also consists of certain other features of construction and combinations of parts hereinafter described, and more particularly pointed out in the claims concluding this specification.

In the accompanying drawings, illustrating the preferred embodiment of my invention, Figure 1 is a central vertical longitudinal sectional view of my machine. Fig. 2 is a right-hand end view, and Fig. 3 is a vertical cross-sectional view on the line $\alpha\alpha$ of Fig. 1.

While the preferred embodiment of my invention is fully shown in the accompanying drawings and its construction and operation are clearly described in this specification, I reserve the right to make such changes from the construction shown and described herein as the scope of the claims hereto appended will permit.

In carrying out my invention I provide a revoluble cylindric screen within a suitable casing, having stock inlet and outlet opening and a trough at one end to receive the refuse or sliver. Said screen is separated into two compartments by a double flexible diaphragm, preferably made of rubber or canvas and secured in any suitable manner to the ends and sides of said screen. The screen is preferably made in two semicircular sections having flanges at their edges, between which the lateral edges of the diaphragm are adapted to be clamped. Between the two folds of the dia-

phragm are arranged semicircular frames, 55 mounted on an offset in a longitudinal shaft extending through the screen-cylinder and carrying a belt-pulley whereby it is operated. The actuation of the shaft with its offset causes said frames and the diaphragm to rise 60 and fall, whereby the pulp is forced out through the screen on first one half of said screen and then the other. The screen-walls preferably diverge from the stock-inlet end toward the other end, provided with the refuse-trough. The refuse-escape slot in the end plate of the screen is adapted to be temporarily covered by a spring-pressed plate operated by a hand-lever.

Referring more particularly to the drawings, 1 is the casing, mounted on uprights 2. 3 is the screen-cylinder, comprising two sections 4 and 5, and 6 is the shaft, having a central offset 7 on which are mounted semicircular frames 8, by means of connecting-rods 75 9, pivotally mounted on longitudinally-arranged rods 9^a, having their ends arranged in blocks 9^b, slidable in slots 9^c in the end plates of the screen. The lateral edges of the diaphragm 10 are clamped between the flanges 80 11 of one section of the screen and the flanges 12 of the other section, and the end portions of said diaphragm are secured to flanges 13 14 on the end plates 15 and 16, respectively, by rivets or other suitable means. The diaphragm 85 is preferably secured to the outer surface of the frames 8 by means of strips 17. The shaft extends at one end through the stationary tubular portion 18 of the pulp-inlet passage. Said shaft carries a pulley 19 at its end, 90 whereby it is actuated. The screen has an extension 20 passing over the tubular portion 18 of the pulp-inlet passage, and said extension carries a pulley 21, whereby the screen is revolved. The end plate 15 extends across 95 the inner opening of the tubular portion 18 and has its edge disposed adjacent to the inner surface of the screen, so that the pulp will be delivered directly to the screen-plates. The other end plate 16 is provided with a 100 series of arcuate apertures 22 around its edge for the escape of the sliver or refuse to the trough 23, secured to the casing and having an outlet 23^a at its lower portion. Said apertures 22 are adapted to be closed by 105 a plate 24, pressed into forcible contact with the end of the casing, so as to close said slot by means of coiled springs 25, mounted on

pins 26, projecting through said plate and carrying nuts 27 on their outer ends. Said plate has a central projection or sleeve 27^a, which is connected to a hand-lever 28, pivoted at 29 to the base of the machine. The said plate is normally closed, but may be opened from time to time to clean out the sliver or refuse from the machine.

In operation the stock is fed to the screen 10 by the inlet-passage and is delivered directly upon the screen-plates, as before described. The centrifugal force due to the revolving of the screen throws the pulp against the plate, while the vibrations of the diaphragm tend 15 to force the fine pulp through the screen-plates. The screen-pulp passes out through the pulp-outlet, while the refuse is allowed to escape by means of its trough, as described.

Having thus described my invention, what 20 I claim as new, and desire to secure by Letters Patent, is—

1. In a machine of the character described, the combination with a cylindric screen, of a flexible diaphragm arranged within said screen 25 longitudinally thereof, and a rotary shaft in said screen having means to cause said diaphragm to vibrate.

2. In a machine of the character described, the combination with a screen, of a double 30 flexible diaphragm and a rotary shaft arranged between the folds of said diaphragm and having means to cause said diaphragm to vibrate.

3. In a machine of the character described, the combination with a cylindric screen, of a 35 double flexible diaphragm and a rotary shaft arranged between the folds of said diaphragm and having means to cause said diaphragm to vibrate.

4. In a machine of the character described, the combination with a cylindric screen, of a 40 double flexible diaphragm arranged therein, and a rotary shaft having an offset arranged between the folds of said diaphragm.

5. In a machine of the character described, 45 the combination with a revoluble cylindric screen, of a double flexible diaphragm arranged therein and a rotary shaft having an offset arranged between the folds of said dia-

6. In a machine of the character described, 50 a cylindric screen in two sections and a flexible diaphragm having its edges fastened between the edges of said sections of the screen and extending across within said screen.

7. In a machine of the character described, 55 a cylindric screen in two sections and a flexible diaphragm having its edges fastened between the edges of said sections of the screen and extending across within said screen, and means to cause said diaphragm to vibrate. 60

8. In a machine of the character described, the combination with a cylindric screen, of a 65 double flexible diaphragm arranged therein and a rotary shaft having an offset carrying a wheel frame or bearing, said shaft arranged between the folds of said diaphragm.

9. In a machine of the character described, the combination with a screen having a flexible diaphragm arranged therein and means to vibrate said diaphragm, said screen having a 70 series of apertures around the edge of one end plate thereof for the escape of the sliver, of means to normally close said apertures and means to simultaneously remove said closure from all of said apertures to clean out said 75 screen.

10. In a machine of the character described, the combination with a screen having a flexible diaphragm arranged therein and a longitudinally arranged shaft therein carrying 80 means to vibrate said diaphragm, said screen having a series of apertures around the edge of one end plate thereof for the escape of the sliver, of a plate adapted to cover all of said apertures and having a central sleeve fitting 85 around said shaft, said plate adapted to move on pins passing therethrough against coiled springs arranged around said pins, and a lever pivoted to a fixture and connecting with the sleeve on said plate whereby the latter may 90 be withdrawn to uncover said apertures.

In testimony whereof I affix my signature in presence of two witnesses.

FRANK M. CHAPMAN.

Witnesses:

W. J. GALLAGHER,
W. L. WRIGHT.

It is hereby certified that in Letters Patent No. 806,640, granted December 5, 1905, upon the application of Frank M. Chapman, of Fort Edward, New York, for an improvement in "Pulp-Screens," errors appear requiring the following correction, viz: In the grant and in the printed head of the specification it is stated that said applicant had assigned "one-third to William J. Gallagher," whereas it should have been stated that said applicant had assigned *three-fourths to said William J. Gallagher*; and that the said Letters Patent should be read with these corrections therein that the same may conform to the record of the case in the Patent Office.

Signed and sealed this 12th day of December, A. D., 1905.
